[57] **ABSTRACT**

Connector and lamp socket structures are disclosed for use in establishing electrical connections between wiring harnesses and lamps. An exemplary lamp socket is designed to provide fool-proof housing panel orientation during installation and a positive pressure interlock assuring a water tight connection with the panel housing.

TWIST LOCK SOCKET WITH CONNECTOR

This invention relates to the establishment of weather-proof electrical circuits between lamp sockets and wiring harnesses. It particularly relates to connectors which form couplings between lamp sockets and wiring harnesses to provide weather-proof electrical connections, and which, once fastened, are hard to remove. The invention has further reference to the assembly of lighting fixtures on a production line, enabling a special lamp socket, complete with a lamp, to be placed in a housing and subsequently permitting a connector and associated wiring harness to be coupled to the lamp socket to complete electrical connections between the lamp and the harness.

The prior art includes lamp sockets which have been complicated and relatively expensive. Many of these prior art lamp sockets have been preconnected to the wiring harness thus avoiding the problems associated with making connections during assembly in automobile assembly plants and the like, but requiring that lamps be installed as a final assembly step in order to avoid lamp breakage. With other prior art lamp sockets it has been necessary to shrink tubing in order to provide a weather-proof seal between the lamp sockets and wiring harness. It has also been necessary in some cases to swedge the lamp socket after assembly to provide a seal between the socket and the lamp housing. This last procedure has meant that the socket is not removable and that the lens will have to be removed to enable replacement of burnt out lamps. With one known device, a pig-tail harness has been employed which required a number of individual connections to the wiring harness in an inefficient and costly manner.

An example of prior art, herein incorporated by reference is to be found in the U.S. Pat. application for a "Lamp Socket", Ser. No. 861,113, filed in the names of James P. Burgess and Melvin W. Polkinghorn on Sept. 25, 1969, and assigned to the same assignee as the present application.

Having in mind the limitations of the prior art it is therefore an object of the present invention to provide a lamp socket and a mating connector incorporating elements that enable the completion of an electrical circuit from a wiring harness through spring contacts within the socket to bulb contacts.

It is a further object of this invention to provide a connector arrangement to enable a wiring harness to be coupled readily to a socket.

It is yet another object of this invention to provide separate socket connectors which, once coupled, resist separation except by application of a much greater force than that required to make a mating fit. This condition assures that the connector elements are unlikely to be separated by accident.

Yet another object is to provide an economical seal between a connector and a socket to prevent moisture from penetrating into a lamp housing.

It is a further object of the invention to provide improved efficiency in an assembly plant by eliminating bulb handling operations through use of sockets in which lamps have been previously inserted.

The above mentioned and other features and objects of this invention and the manner of obtaining them will become more apparent, and the invention itself will be best understood by reference to the following description of an embodiment of the invention taken in conjunction with the accompanying drawings, in which:

FIG. 1 is a sectional view of an embodiment of the assembled lamp socket structure illustrating a completed connection between a wire harness connector and a lamp socket,

FIG. 2 is a bottom view of the assembly of FIG. 1,

FIG. 3 is a top view of the assembly of FIG. 1, with the bulb removed,

FIG. 4 is a perspective view, partially in section, illustrating certain features of a lamp socket according to the invention,

FIG. 5 is an exploded schematic perspective view showing components of the lamp socket and the connector,

FIG. 6 is a rear perspective view of the lamp socket showing the connector in place and the relative position of the weatherproof boot seals,

FIG. 7 illustrates three models of the invention representing the adaptability of the invention to different focal ranges,

FIG. 8 is a bottom view of the upper portion of the lamp socket showing the locking shoulders and detent,

FIG. 9 illustrates the adaptability of the invention to housing panels of different thicknesses, while FIG. 9A shows a configuration of the lamp socket integral to the lamp housing,

FIG. 10 shows the lamp socket structure locked into engagement with a housing panel,

FIG. 11 shows a view of the cable end of the connector,

FIG. 12 is a sectional view of the connector,

FIG. 13 is a view of the end of the connector which couples to the base of the lamp socket,

FIG. 14 is a sectional view showing details of a tower in the connector,

FIG. 15 is a further view of the connector tower illustrating the manner in which the cable strands are coupled to the connector,

FIG. 16 shows a lamp socket mounted in place in a reflector housing with a connector and cable harness aligned for assembly,

FIG. 17 shows the connector and cable harness after coupling to the socket in FIG. 16, and

FIG. 18 is a view of an assembled socket and connector after removal from the reflector housing.

GENERAL DESCRIPTION

This invention relates to a lamp socket and connector structure having relatively few parts, making it easy to fabricate and assemble. The external configuration of the lamp socket structure insures straight-line and fool-proof orientation of the lamp socket with the housing panel opening during installation. The connector provides a good connection between the lamp socket structure and a cable harness.

The lamp socket structure assembly is provided with a unique resilient compression ring and detent arrangement which insures a positive pressure interlock with the housing wall and which provides against accidental dislodgment of the lamp socket structure from its operative use position on the panel housing. The compression ring cooperates with the annular shoulder of the lamp socket so as to accommodate housings constructed of various materials and having various wall thicknesses.

The overall design of the lamp socket and connector structure provides equipment which can be quickly, easily and economically assembled into the lamp socket housing. No complicated fabrication steps are required to manufacture and assemble this structure.

As shown in the drawings and described in the specification, the lamp socket structure of the instant invention is adapted to quickly, easily and lockably receive the connector which, in turn, is coupled to the individual wire leads of the wire harnesses utilized in the external electrical system of the vehicle.

With the connector inserted into the lamp socket structure, the wire leads of the wire harness are coupled to the individual contact elements contained within the lamp socket structure. However, the wire leads are not otherwise connected to the individual contact elements, and the individual contacts are automatically kept free of pressure from external wire harness strains. In this way, bulb contact pressure is independent of external wire harness strains, thus eliminating one of the main problems encountered in the devices of the prior art.

Furthermore, as shown in FIG. 7, the unique construction embodied in the lamp socket structure permits its adaptability to provide a variety of focal ranges while maintaining the same basic internal structural features and the same internal interrelationship of its components.

A completely internal ground circuit capability is provided which enables the lamp socket structure to be used with either metal or plastic housings.

The lamp socket structure also incorporates therein a built-in structure which is useful in assembly and which provides for the use of fiber optic channels, if desired.

The lamp socket structure is operated in such a manner and is so configured that only a single reflector (housing) opening is required. No irregular surface is required on the housing for detenting.

The lamp socket structure is constructed so that there are no exposed electrical contacts, thus providing a lamp socket which is not only safe in operation but which is not susceptible to failure due to dirt or other foreign particles finding their way into the internal portion of the structure.

Furthermore, unique boot seals are utilized which provide individual wire lead sealing and which cooperate with the lamp socket structure to provide a protected boot seal-lamp socket body juncture.

All of the foregoing structural features not only provide a lamp socket and connector structure which is simple and economical to fabricate and install, but one which meets the stringent safety standards now being imposed on the automotive industry.

SPECIFIC DESCRIPTION

Turning now to specific details, a partial section of an assembled lamp socket structure is shown with a sectioned connector attached in the embodiment of FIG. 1 of the drawings. The lamp socket structure, indicated in general by the arrow 21, includes a flange collar element 22 and a main body 23. The main body housing 23 is provided with a bulb receiving cavity 24 at one end which is adapted to receive a twist lock bulb 25 therein. A contact receiving and retaining cavity 26 is provided within the central part of the body housing 23. The contact receiving cavity 26 is in open communication with the bulb receiving cavity 24. Contact elements 27 are inserted through the bulb receiving cavity 24 into their operative use position in the contact cavity 26. Each of the contact elements 27 is provided with a resilient curved bulb contacting portion 28 at one end thereof. Further, each of the contacts 27 is provided with a reverse leaf spring extension 29 which is adapted to slidably, wipingly and springingly make contact with terminal plugs 31 inserted into the lamp socket structure. A lip extension 30 is provided within the contact cavity 26 so as to lockably retain the contacts 27 therein. Upon insertion of the contacts 27 into the contact receiving cavity 26, the leaf spring extension 29 springs outwardly behind the lip extension 30 so as to prevent accidental removal or dislodgment of the contacts 27 from the contact cavity 26.

The terminal plugs 31 are held in terminal plug socket cavities 6 of a connector C. The connector C incorporates extension towers 4 located within a protective skirt 8 sealed in this view to the socket 21 by a seal at 15. The terminal plug socket cavities 6 are positioned in the connector C so that terminal plugs 31 placed therein come into positive slip-proof wiping contact with the leaf spring extensions 29 of the contact elements 27.

FIG. 2 illustrates, in a simplified way, the arrangement of the base of the lamp socket structure of FIG. 1 with the connector removed from view. In this figure, the flange 37 is shown to have ridges at 41 and 43 as well as an optic tower at 4'. Components to receive a connector C are indicated at C'.

As shown in FIG. 3, a standard ground contact element 36 is provided on the lamp socket structure 21 to engage the base of a bulb element mounted therein. The upper ring collar element 22 is provided with an annular flange portion 37 having a circumferential seating lip extension 37a which is configured to seatably and retainably engage a resilient compression ring member 38 (FIG. 1). As will be hereinafter described, the compression ring 38 cooperates with the base of annular shoulders 39, 40 and 41 of the ring element 22 to retainably engage a reflector housing wall therebetween.

The ring collar element 22 is provided with positive orienting or aligning shoulders 39, 40 and 41 as shown in FIG. 3, which are configured to matingly engage corresponding recesses in the opening provided through the reflector housing panel into which the lamp socket structure is mounted.

Turning back to FIG. 1, a waterproof rubber boot seal 10 is selectively provided for mating engagement with the external walls of the extension towers 4 which define terminal plug socket cavities 6. The boot seal 10 is provided with an opening

5 12 through which the terminal plug 31 passes to be locked into the connector C within the socket cavity 6. The boot seal opening 12 is normally covered by a thin wall membrane which is punctured when the terminal plug 31 is inserted therethrough. Further, the opening 12 actually stretches to accommodate the terminal plug 31, thus providing a weather-proof fit around the terminal plug 31 which prevents moisture and/or foreign particles from entering the interior of the lamp socket structure.

15 It should be noted that the ring element 22 can be placed in a variety of positions along the longitudinal axis of the main body housing 23 so that the lamp socket structure can be adapted to various focal lengths. After ring element 22 has been properly positioned on the body housing 23 so as to 20 achieve the desired focal range, it is then ultra-sonically joined or heat staked thereto at selected points along juncture lines 43 and/or 44.

Views showing additional aspects of an embodiment of the invention are provided in the perspective view of FIG. 4 and in 25 the exploded schematic view of FIG. 5. FIG. 5, in particular, shows in detail the various components of an embodiment of the lamp socket and connector structure. Weatherproof boot seal units are shown at 10 with terminal plug openings 12 therethrough. Each of the individual boot seal units 10 is 30 cylindrically configured to matingly engage the external walls of the individual terminal plug cavity socket extension towers 4. The protective skirt 8 of the connector C is shown with slots at 74 and 74' to engage elements on the opposite side (see 41, FIG. 2) of an annular pressure ring retaining flange 37. A 35 lower body housing 55 is provided which contains contact spring cavities 26 and a ground strap cavity or channel 50 therein which are in open communication with the terminal plug cavities 57 as will be hereinafter described. The body housing 55 is provided with three guide retaining arms 58, 59 and 60, respectively, that are adapted to matingly engage the 40 upper body housing 61. The lower body housing 55 is provided with an annular compression ring retaining flange 37 and circumferential lip extension 37A upon which the compression ring member 38 is seated.

45 Contact elements 63 and 64 are provided having curved bulb contact portions 65 and 66 at one end thereof, respectively, and leaf spring terminal plug contact portions 67 and 68 at the opposite end thereof. It should be noted that the contact elements are configured so that the tip ends 69 and 70 of the contact elements bear against the mid-portion of the contact elements. This tends to impart a more positive contact pressure against the base of the bulb inserted thereagainst.

50 A ground strap element 71 is provided having a curved end portion 72 which is adapted to engage the upper body housing 61. The ground strap 71 is also provided with a leaf spring extension 73 which is adapted to engage a terminal plug element 31 inserted into the terminal plug receiving cavity.

55 The upper body housing 61 is provided with a bulb engaging cavity 74 therethrough. Suitable grooves 75 are provided within the bulb engaging cavity 74 which are adapted to lockably engage the ears on the base of a standard twist lock bulb.

Orienting alignment shoulders 77, 78 and 79 are provided 60 on the upper body housing 61. The alignment shoulders 77, 78 and 79 have different thicknesses and are configured to matingly engage corresponding recesses provided in the opening in the lamp socket reflector housing into which the lamp socket structure is mounted. This alignment or orienting feature insures that the lamp socket structure can only be inserted into the reflector housing in its proper use position. Thus, the result is fool-proof installation of the lamp socket structure into the lamp socket reflector housing.

65 A tower 80 is provided on the lower body housing 55 which 70 may be adapted to receive an optical fiber therethrough for

aiming at the filament of the bulb. This tower serves also as an aid in positioning the lamp socket relative to the reflector housing.

As shown in the rear perspective view of FIG. 6, the connector C is provided with a plurality of extension towers 4. Each of the towers 4 defines a terminal plug socket cavity 6 therethrough. Here again the connector C is also provided with a protective skirt 8 which is coextensive with the extension towers 4. In use, the skirt 8 acts as a protective guard for the towers 4 and the boot seal units 10 mounted thereover. The presence of the protective skirt 8 on the connector C permits its installation on the lamp socket structure without any manual handling of the boot seals 10 or of the terminal wire ends leading into the socket cavities 6. The worker merely grasps the external protective skirt 8. Thus, there is very little likelihood that damage will occur to the boot seal connection or individual wire leads during the installation process.

Each of the individual boot seal units 10 has a cylindrical configuration for mating engagement with the cylindrical outer wall of the extension tower 4. The boot seals 10 represent a distinct improvement over the boot seal structures of the prior art. The boot seal structures of the prior art have been mounted over the entire base of the lamp socket structure. The peripheral sealing edge of the prior art boot seal structure has been located on the exposed outer wall surface of the lamp sockets, thus exposing them to damage and to failure of the sealing action. Failure of the boot seals of the prior art have exposed all of the circuits leading into the lamp socket structure. However, the boot seals 10 of the instant invention provide independent sealing for each circuit. The result is a more readily controllable seal joint because the sealing action is around each individual wire element and not around the entire lamp socket body housing.

It should also be noted that the unique seal design requires substantially less rubber material than the relatively massive boot seals of the prior art. This brings about a significant cost reduction in the overall cost of the lamp socket structure. The design of the boot seals 10 can be varied as desired as long as they provide a water and dirt proof seal for the connections between the terminal plug elements and the connector.

In FIG. 7, three different models of the lamp socket structure are shown to illustrate how the lamp socket structures can be readily adapted to provide for three different focal ranges. While the external configuration of the upper body housing 61 (including C' from FIG. 2) vary in the different models, the connectors C and the internal interrelationships of the various components, channels, socket cavities and the like, remain constant. The relative positioning of the external flange 62 and of the shoulders 77, 78 and 79 on the lamp socket structure is changed on each model so that the position of the lamp socket structure is axially adjusted in relation to the housing panel upon which it is mounted. This enables the production of different focal ranges as desired, without changing connector tooling. In essence, only the plastic tooling needs to be changed for each model; the metal tooling remains the same.

As shown in the bottom view of FIG. 8, the upper body housing 61 of an exemplary embodiment of the lamp socket may be provided with three longitudinally extending orienting or alignment shoulders 77, 78 and 79, respectively. Shoulder 78 is provided with a detent extension 83 at the base thereof which engages a slot provided in the housing panel to lockably retain the lamp socket structure thereon. Shoulder 77 is provided with a stop shoulder 84 at the base thereof which also cooperates with the housing panel to effect a positive seating of the lamp socket structure into its operative use position. Shoulder 79 may be provided with an optical fiber channel 49 therethrough and may support an optical director tower 80 thereon.

The adaptability of the lamp socket structure to operatively engage housing panels of varying thicknesses is shown in the composite view of FIG. 9. The upper portion of the composite view of FIG. 9 illustrates engagement of the lamp socket structure with a thin housing panel 86. The compression ring 38

compresses sufficiently to permit engagement of the housing 86 between the compression ring 38 and bases of the alignment shoulders 77, 78 and 79, respectively, which are positioned on the upper body housing 61. As previously described, the compression ring 38 is seated upon the annular flange 37 of the lower body housing 55.

5 The lower portion of the composite view of FIG. 9 illustrates engagement of the lamp socket structure with a relatively thick housing panel 87. As shown, the compression ring 38 is merely compressed to a greater degree to accommodate the thicker housing panel 87. This capability to automatically adjust to a variety of panel housing thicknesses clearly imparts 10 great versatility to the lamp socket structure. Thus, lamp socket structures can be mass produced for use in equipment where wide variations in the thickness of different types of 15 housing are encountered.

Further, the use of the compression ring 38 provides a positive and relatively vibration-free engagement of the lamp socket structure with the housing. Inasmuch as the compression ring 38 is actually compressed when the lamp socket structure lockably engages the housing, the compression ring 38 exerts a constant retentive pressure against the back of the housing during the entire period in which the lamp socket structure is mounted in the housing.

20 Further use of a connector C'' similar to the connector C with a socket is illustrated in FIG. 9A. In this Figure, a lamp socket is molded as a part of a lamp housing at H. The connector C'' is attached to the harness and may be sealed at the 25 point of wire entry by a boot 10. To complete the socket assembly an upper socket 63 is attached to the housing by heat staking or ultrasonic means after the socket terminals have 30 been located inside the assembly. The fingers 89 protruding from the connector have leading angles 91 which enter the appropriate slots 92 of the socket until the locking edge 93 passes the shoulder 94 on the socket structure.

35 These fingers have sufficient resiliency to allow the connector to be easily engaged while the force required to disengage the two pieces is quite large. Removal of the connector is accomplished by inserting a screw driver or similar device in the slot 95 and twisting to overcome the large angles of the finger engagement. The additional cavity 96 fitting into the irregular slot provides a means of orienting the connector to the housing.

40 The skirt 8'' of the connector C'' surrounds the socket body limiting the amount of dirt and moisture which gets to the flat part of the connector 97 where a compression seal 98 is in contact with a sealing lip 99 of the socket. This seal prevents any moisture, dust, etc. from entering the lamp housing. The 45 location of the slot 95 mentioned above precludes any interference with the removal tool of the rubber seal during the forceable removal of the connector from the socket.

45 The cross-sectional schematic side view of FIG. 10 illustrates the lamp socket structure in its operative use positions 50 on a housing 87. The detent 83 is shown in its lock position in a suitable recess provided in the housing panel 87. The compression ring 38 is shown in its compressed position between the annular flange 37 and the housing 87.

55 It is important to note that the lamp socket structure can be fabricated independently of the fabrication of the wire harness utilized therewith. During fabrication thereof, the wire harness is merely provided with terminal plug elements 31 at the ends of the terminal wires 90 of the wire harness (FIGS. 16 - 60 18). Previously, the lamp socket structures have been attached to the wire harnesses during fabrication thereof. Damage to the lamp socket structures has occurred during 65 fabrication of the wire harnesses.

65 In the instant invention, the wire harness is fabricated and then the terminal plug elements 31 are inserted into the completed connector. The wire harness structure then can be quickly and easily connected to the lamp socket structure.

70 A more detailed showing of a connector C is presented in FIGS. 11 - 14. FIG. 11 illustrates the cable end of the connector, FIG. 12 is a sectional view along the lines A-A of FIG.

11, FIG. 13 illustrates the socket end of the connector, FIG. 14 is a sectional view taken along lines B—B of FIG. 13 and FIG. 15 illustrates the manner of connecting the connector to a cable terminal.

Three towers 4 in the connector C include internal passages 5 which vary in diameter by a plurality of steps as best shown in FIG. 14. The steps permit easy entry of cable terminals. The bases of the towers terminate at 5 to form ledges against which latching elements 7 of the terminals 31 of cable wires may be secured against removal from the towers. 10

Means are provided at 14, 15 and 16 which serve to engage suitable slots 17 (FIGS. 9 and 10) on the outside lower portion of the lamp socket and to lock the connector to the socket.

At the time the connector engages the lamp socket, three terminals 31 of a cable will be connected to respective contact elements, such as 67, 68 and 73 in FIG. 5. In FIG. 15, a terminal 31 of the cable is shown being held in position in the passage 6 of a tower 4 by a latching element 7 which engages the ledge 5. 15

FIG. 16 shows a portion of a reflector housing 87 with 20 which the invention has utility. This figure shows also the lower portion of a lamp socket C' positioned in the housing 87 in position to receive the connector C and the associated cable harness 90. It should be noted at this point that C and C' may be separated after they have been placed together, as in FIG. 25 17. Generally, the mating elements on the lamp socket side (17 in FIG. 9) and the corresponding elements in the connector are formed to be mated more easily than they can be separated, but they are designed to be separable if necessary.

FIG. 17 is a representation of the connector C engaged with the lamp socket after having been pushed in the direction of the arrow. In this view the tower 80 and the flange 37 are seen, though the socket itself is hidden from view. It will be appreciated that the connection between the connector C and the socket shown in FIG. 17 are accomplished simply by pushing the connector over the socket in the direction indicated by the arrow. 30

In order to remove the assemblage of lamp socket, connector and cable from contact with the reflector housing, it is necessary only to push the assembly slightly and twist it 40 counter clockwise in the direction of the arrow in FIG. 18 to disengage it, after which it may be pulled from the opening 88. FIG. 18 illustrates the appearance of the assembly after it has been removed from the housing in this manner.

It will be seen that a lamp socket and connector structure is 45 provided which can be easily fabricated. The unique design thereof permits quick assembly of the components into the lamp socket structure of the instant invention. Further, the use of a compression ring provides positive and relatively vibration-free engagement with housing panels of varying 50 thicknesses. Finally, the lamp socket structure is adapted to lockably receive the connector elements therein and maintain the same in positive, wiping strain-free contact with the contact elements contained in the lamp socket structure. 55

Various other modifications of the invention may be made without departing from the principle thereof. Each of the modifications is to be considered as included in the hereinafter appended claims unless these claims by their language expressly provide otherwise.

We claim:

1. Connector structures for mating a lamp socket to a wiring harness comprising:
a first connector element including an extension tower and a protective skirt,
a first portion of said protective skirt providing protection for the extension tower,
said first connector element, in cooperation with said extension tower, providing means for receiving and holding a terminal plug of a wiring harness,
a second portion of said protective skirt including first latching means by which a second connector element may be engaged, 70

said second connector element including second latching means to engage the first latching means and form a lamp socket in combination therewith,
the second connector element including a receptacle for receiving a bayonet mounted electric lamp and spring biased contact elements within the receptacle which latch into a cavity within the receptacle to conductively engage the terminal plug of the wiring harness and enable completion of an electrical connection between the wiring harness and the receptacle.

2. Structures as claimed in claim 1, in which the first latching means includes a plurality of retainer elements within the second portion of the protective skirt, and the second latching means includes a plurality of retaining elements located on the periphery of the second connector element.
3. Structures as claimed in claim 2, in which the second portion of the skirt encloses a flat compression seal forming a complete and water tight seal between the first connector element and the second connector element when they are engaged.
4. Structures as claimed in claim 2, in which the fit of the first latching means to the second latching means allows for a low force engagement and requires a high force disengagement as determined by the lead angles and locking angles on mating surfaces in the skirt and on the second latching means.
5. Connector structures as claimed in claim 1, in which the second connector element includes structures enabling the second connector element to be mounted through a mating opening in a thin wall housing.
6. Connector structures as claimed in claim 5, in which locking elements are provided as a part of the second connector element to enable positive locking with a reflector housing.
7. Connector structures as claimed in claim 6, in which the reflector housing includes a recess, and the second connector includes a detent to engage the recess and assure positive locking.
8. Connector structures as claimed in claim 1, in which the terminal plug of the wiring harness includes a latching element, and the means for receiving and holding the terminal plug includes the extension tower and a ledge formed in the first connector element around one end of the extension tower to engage the latching element and secure the end of the terminal plug from withdrawal.
9. Structures as claimed in claim 1, in which the second portion of the protective skirt and second latching means include mating elements serving to prevent them from rotating relative to each other.
10. Structures as claimed in claim 1, in which means are provided in said second connector element to enable a covered ground connection to be made to the first connector element.
11. Connector structures as claimed in claim 5, in which the second connector element may be adjusted to permit usage in housings requiring centering of lamp filaments at different focal points.
12. Structures as claimed in claim 1, in which the second connector element includes a lamp housing.
13. Structures as claimed in claim 1, in which the second connector element is formed as an integral part of a lamp housing.
14. Structures as claimed in claim 1, in which the spring biased contact elements include a resilient curved contact portion for establishing electrical contact with the base of an electric lamp and a reverse leaf spring extension to slidably, wipingly and springingly make contact with the terminal plug of the wiring harness.
